DESIGN FOR A COMBINED FIRE DETECTOR, ALARM, AND EXTINGUISHER

Joseph Grison, New York, N. Y.

Application March 12, 1936, Serial No. 61,605

Term of patent 7 years

To all whom it may concern:

Be it known that I, Joseph Grison, a citizen of the United States, residing at New York, New York, have invented a new, original, and ornamental Design for a Combined Fire Detector, Alarm, and Extinguisher, of which the following is a specification, reference being had to the accompanying drawing, forming a part thereof, in which

Fig. 1 is a perspective view of a combined fire detector, alarm, and extinguisher showing my new design.

Fig. 2 is a front elevational view of the combined fire detector, alarm, and extinguisher shown in Fig. 1.

The dominant feature of the design resides in the casing shown in solid black lines.

I claim:

The ornamental design for a combined fire detector, alarm, and extinguisher, as shown and described.

In witness whereof, I affix my signature.

JOSEPH GRISON.
